(57) **CLAIM**

The ornamental design for a modular plant growth apparatus, as shown and described.

DESCRIPTION

FIG. 1 is a perspective view of a modular plant growth apparatus with a cutaway break line in the length of the apparatus; FIG. 2 is a partial view of the modular plant growth apparatus of FIG. 1 illustrating the plant growth wells; FIG. 3 is a front view of the modular plant growth apparatus of FIG. 1 with a cutaway break line in the length of the apparatus;

FIG. 4 is a side view of the modular plant growth apparatus of FIG. 1 with a cutaway break line in the length of the apparatus;

FIG. 5 is a back view of the modular plant growth apparatus of FIG. 1 with a cutaway break line in the length of the apparatus;

FIG. 6 is a top view of the modular plant growth apparatus of FIG. 1;

FIG. 7 is a bottom view of the modular plant growth apparatus of FIG. 1;

FIG. 8 is a top view of the modular plant growth apparatus of FIG. 1, illustrating the growth apparatus in an alternate curved orientation; and,

FIG. 9 is a perspective view of the modular plant growth apparatus of FIG. 1 with a cutaway break line in the length of the apparatus.

In the drawings, the broken lines depict environmental subject matter only and form no part of the claimed design.

The modular plant growth apparatus is shown with a symbolic break in its length. The appearance of any portion of the article between the break lines forms no part of the claimed design.

1 Claim, 5 Drawing Sheets
